PIANO CONSTRUCTION HAVING A CURVED BACK

Herbert E. Thyen, Jasper, Ind., assignor to W. W. Kimball Company, Jasper, Ind., a corporation of Delaware
Filed Apr. 20, 1964, Ser. No. 361,067

4 Claims. (Cl. 84—184)

The present invention relates to pianos, and more particularly to a piano back construction, especially for upright pianos such as spinets, studio consoles, and the like.

At present, conventional piano back construction of the nature referred to comprise heavy substantially uniformly spaced posts, arranged vertically along the back of the piano, and glued, dowelled, or otherwise fixedly secured to upper and lower rail members to provide a rigid box like construction capable of withstanding the tensional forces developed of many tons by the piano strings when these elements are tightened up when the piano is tuned.

It is apparent that piano backs of the conventional type as described must necessarily be heavily constructed to provide for the rigidity and strength needed to withstand the forces encountered through string tensioning. Conventional piano back constructions therefore contribute substantially to the overall weight of the piano, as well as being expensive and complex to construct.

With the foregoing in mind, an object of the present invention is the provision of a piano back of lighter construction than has heretofore been possible without sacrifice of strength or rigidity thereof.

Another object of the present invention is the provision of a piano back construction which is economical to make and easy to assemble, and which presents a pleasing appearance, while providing for good tonal quality.

A further object of the present invention is the provision of a piano back construction which is able to withstand the stresses and strains encountered in moving of the piano without materially effecting the tuning thereof.

A still further object of the present invention is the provision of a piano back construction which is so constructed and arranged as to provide uniformly distributed reaction against those loads imposed on the back by forces produced by the tensioning of the piano strings.

A still further object of this invention is the stabilization of the piano back from the effects of humidity and temperature.

Other objects and advantages of this invention will become more apparent upon reference to the following specification taken in connection with the accompanying drawings wherein:

FIGURE 1 is a perspective view of an upright type piano as viewed from the back thereof;

FIGURE 2 is a partial sectional view taken along line 2—2 of FIGURE 1 and showing the novel back construction of the present invention;

FIGURE 3 is a longitudinal section taken along line 3—3 of FIGURE 1; and

FIGURE 4 is a perspective view illustrating one edge of the piano back construction and the manner of assembling.

Referring to the drawings, FIGURE 1, generally indicates at 10 a piano of the upright type embodying the novel back construction of the present invention. The novel back construction, generally indicated at 11, comprises an upper rail 12 having a concave surface 13 extending the entire length of one side thereof, a lower rail 14 having a concave surface 15 extending the entire length of one side thereof, a pair of side members 16

2

provided with concave notch means 17 extending along the full length of the inner edges of the side members, a slightly arched sounding board 18 having a plurality of reinforcing rib members 21 uniformly spaced therealong on the back, and a laminated, arched support panel indicated by reference numeral 22. Rails 12, 14 and 16 are rigidly interconnected in a known manner to form a strong frame.

The panel 22 is fixed to the rails, as is the sounding board 18 to form a unitary back structure. The arched support panel 22 may be provided with a plurality of spaced apertures 30 therein which provide outlet means for tones developed in the resonant chamber 32 formed between the sounding board 18 and the arched support panel 22. This chamber is indicated in FIGURE 2.

Support panel 22 is preferably formed of a plurality of large rectangular wooden plies laminated in a conventional manner to form a thick composite board possessing extreme rigidity and strength. Hardwood or softwood veneers or combinations of the two, in species such as used for the cabinet and sounding board is a suitable material.

The support panel 22 is preformed to an arched configuration, substantially as shown in FIGURES 1 and 2 either at the time of laminating or subsequent thereto. The preformed support panel 22 is then glued, dowelled or otherwise secured at its longitudinal edges at upper and lower regions 24 and 26, respectively, in mating relation to curved surfaces 13 and 15 of upper and lower rails 12 and 14, respectively. The support panel 22 is also glued, dowelled or otherwise secured to side members 16 at the exposed edges 28 of the panel in mating relation to concave notch means 17. The conventional sounding board 18 is securely positioned to the rails 12, 14 and 16 as indicated at 29 to form the completed piano back construction of this invention.

The mechanism necessary for generating the tones delivered to the sounding board 18 is partially shown in FIGURE 2 of the drawings and is of conventional nature comprising a multiplicity of strings 34 which are struck by felt covered hammers 36 and associated means (not shown) to generate the desired tones. The strings 34 are connected to the string plate 38 and pass over a bridge 40 and terminate at a wrest plank 42.

Strings 34 connected between string plate 38 and wrest plank 42 and disposed over bridge 40 are drawn tightly by tuning pins 44 to tune the piano. The total force produced by the tensioning of the strings is on the order, as previously stated, of about 18 tons.

The arrangement of the present invention eliminates the usual multiplicity of vertical rails disposed between the top and bottom rails of a conventional piano back, thus substantially lightening the structure and making it more inexpensive to construct while not in any way detracting from the high strength that must be present in a piano back structure. The arched formation of the back panel disposes it in relation to the top and bottom and side rails of the piano back so that it imparts as much strength to the piano back as was formerly obtained by the heavy vertical rails or posts set between the top and bottom rails inwardly from the ends.

At the same time, the provision of the back establishes the chamber between the back panel and the sounding board, which has been referred to above as a "resonant chamber" and this can substantially enhance the tonal qualities of the instrument even when the curved back panel is not provided with apertures.

The apertures referred to and illustrated in the drawings in the back panel are provided when they will improve the tonal qualities of the instrument and the size and distribution of these apertures will be determined by the tonal qualities obtained. These apertures may be uniformly dis-

tributed, but it could also be the case that non-uniform distribution and/or size of the apertures would produce the best results.

It will be apparent that the arching of the back panel 22, in addition to giving greater strength to the piano back, also exposes portions of the end rails on the insides that could be availed of for setting in hand grips of a more or less conventional type to assist in the moving of the piano.

The piano back structure according to the present invention is easily cleaned and is not subject to deterioration and is readily adaptable to various sizes of pianos. For example, a conventional piano back might require a panel measuring from about thirty inches to somewhat more than forty inches in height, and this panel might be on the order of sixty inches in length. In thickness, the curved back panel may vary, and may be more specifically determined by a choice of species of wood veneer, the number of plies, the thickness of individual plies, and the grain direction of these plies. The plies are permanently bonded together with a moisture resistant adhesive and, as mentioned, formed to an arched configuration either at the time of laminating or subsequent thereto. The greatest strength can be obtained by curing the panel in its curved configuration. The plies of the laminated back would, of course, be arranged with their respective grain directions crossing, which would provide for the greatest strength of the finished product.

It has been mentioned that the back panel could be glued and dowelled to the rails, but it is also possible for this member to be secured in position by large screws, preferably with the use of locating dowels in addition to the screws.

It will be apparent from the foregoing description, that a piano back construction has been provided forming an extremely strong and durable structure having the necessary properties for withstanding the stresses transferred to the back by the strings 34. Further a piano back construction is provided which is neither bulky nor excessively heavy, as compared with present piano back constructions, and wherein the tonal quality of the instrument is not only not deleteriously effected but is enhanced.

It will be understood that this invention is susceptible to modification in order to adapt it to different usages and conditions; and accordingly, it is desired to comprehend such modifications within this invention as may fall within the scope of the appended claims.

I claim:

1. A piano back construction comprising: a pair of spaced horizontally arranged top and bottom rail members of substantial cross section, a pair of vertically arranged spaced side members secured to the opposite ends of said upper and lower rail members and also of substantial cross section, said members making up a substantially rigid frame forming the frame of the piano back, sounding board means mounted on said frame on the side thereof toward

the inside of the piano, arcuate groove means formed along the inner edges of said side members on the other side of the frame, a laminated arched support panel mounted on the said other side of said frame in spaced relation to said sounding board with the convex side directed towards said sounding board and having its peripheral portions on said convex side in engagement with said top and bottom rail members and in engagement with said side members at the bottoms of said arcuate groove means, and means fixedly securing the peripheral portion of said panel to said frame.

2. A piano back construction comprising; top and bottom rail members of substantial cross section, side rail members secured to the opposite ends of said upper and lower rail members, and also of substantial cross section, said members making up a substantially rigid frame forming the frame of said piano back, said top and bottom members being bevelled off toward the inside of the frame on the one side of the frame which is toward the outside of the piano, arcuate notches formed on the inner edges of said side rail members on said one side of the frame, a sounding board mounted on said frame on the other side thereof, tone generating means mounted on said sounding board on the opposite side thereof from said frame and comprising strings, a string plate, a wrest plank, and a bridge, a laminated arched support panel on said one side of said frame concave outwardly of said frame and having its upper and lower edge portions in engagement with the bevelled off portions of said top and bottom rail members and having its side edge portions positioned in said arcuate notches and bearing on the bottoms thereof, means fixedly securing said edge portions of said support panel to said frame, said support panel being in spaced relation to said sounding board so as to define a chamber therebetween.

3. A piano back construction according to claim 2 in which said support panel has aperture means of substantial size formed therein extending from the concave side of said support panel into said chamber.

4. A piano back construction according to claim 3 wherein said aperture means comprise a plurality of apertures distributed over the length and height of said support panel.
